TABULATING MACHINE

Clair D. Lake, Binghamton, N. Y., assignor to International Business Machines Corporation, New York, N. Y., a corporation of New York

Application January 17, 1934, Serial No. 796,927

6 Claims. (Cl. 235—61.9)

This invention relates to tabulating machines of the type wherein data are taken from perforated cards to control accumulating and printing operations of the machine.

5 The main object of the invention is to improve generally upon machines of this character; as for instance by so constructing and arranging the parts and the mode of operation as to obtain greater operating speed and a higher degree of 10 reliability than is at present possible.

It is a desideratum in certain types of work performed by tabulating machines wherein a list of items is printed under record card control and a total of the items printed as an accompaniment 15 to the itemized list, to obtain a total which is truly representative of the sum of the printed items.

It is the object of the present invention therefore to so re-organize the interrelation between the accumulating and printing devices of the tabulating machine, that, where a printed list is accompanied by a printed total, the agreement of such total with a known figure will be a certain indication that the items as listed are correct. This result has been achieved by providing an improved type of printing mechanism of the reciprocating type bar form, wherein each type bar is to close an individual contact at the time one of its type elements is selected for printing. The contacts are adapted to control the energization 20 of the adding magnets, so that an impulse is transmitted to an adding magnet when a type element is selected. It is thus obvious, that the actuation of the accumulator is dependent upon and incidental to the actual type element selecting operation, which, once effected, is certain to result in the printing of the character selected. If, due to any cause, the character selected for printing is not the desired one, the value entered into the accumulator will be correspondingly undesirable, so 25 that there is a certitude that a total printed under such conditions will be truly representative of the printed list of items which it ordinarily follows.

A further object of the invention, is to provide an improved form of checking mechanism which has particular advantage in connection with the preparation of bills or statements, as issued, for example, by public utility companies. In the preparation of these statements, it is customary to print certain data in a plurality of places on the bill, for example, on the stub, coupon, and the bill portion proper. Other objects reside in new and improved structures and cooperations with the special elements of the mechanisms.

55 As will be pointed out, the invention is illus-

trated by way of example in the drawings in which:

Fig. 1 is a wiring diagram of the electrical circuits of a complete tabulating machine to which the present invention has been applied. 5

Fig. 2 is a sectional detail of the essential elements of the printing mechanism of the tabulator showing the manner in which the mechanism of the invention is applied thereto.

Fig. 3 is an isometric view showing the essential operating elements of the accumulator mechanism. 10

Fig. 4 is a detail view showing the arrangement of the type bar controlled devices.

Figs. 5 and 6 are time charts of certain of the contact devices employed in carrying out the objects of the invention. 15

The wiring diagram shown in Fig. 1 is similar to that of the printing tabulator disclosed in the patent application of C. D. Lake and G. F. Daly, 20 Ser. No. 672,388, filed May 23, 1933, now Patent No. 1,976,617, granted October 9, 1934.

The circuit connections as shown in the aforesaid application are shown in light lines in Fig. 1, and the connections added thereto for the purpose 25 of carrying out the present invention have been superimposed thereon in heavy outline.

During card feed and analyzing operations, the machine is driven by a tabulating motor TM, which is controlled by a group of circuits including relays and cam operated contacts, and during total taking operations, the machine is driven by motor RM, which is also controlled by relays and cam controlled contact devices, which are illustrated in the upper portion of Fig. 1. During the 30 operation of the motor TM, the usual perforated cards will feed successively past a set of upper analyzing brushes UB and then past lower analyzing brushes LB. As they pass the latter, the items represented by the perforations may be entered 35 into accumulators, represented by accumulator magnets 10, and printed under control of printing magnets 11. The cards continue to feed and the successive items continue to be entered as long as certain classification holes do not change, this 40 being taken care of by the usual group control GC. On a change in the group classification perforations, the group control system interrupts accumulating. During the ensuing total taking operations, printing is controlled by the printing magnets 11 in a manner to be more fully explained. 45

Each card column contains 10 index point positions, differentially located to represent the 10 digits, and a different digit is represented by a perforation in each position. As the card passes 50 55

the lower brushes LB the position of its index points determines the time of closure of circuits. A representative plug connection for printing is shown on Fig. 1 where a plug connection 12 may be made between the selected lower brush and a plug socket 13 associated with the selected denominational order of the accumulator. As the selected column passes the lower brush, a circuit will be completed upon the analysis of a hole, which is traceable as follows: from the right side of line 14 through lower card lever contacts 15, contact devices 16, lower brush contact bar 17, perforation in the record card, connection 12, socket 13, normally closed contacts 18a, printing magnet 11, to left side of line 19. This is the normally effective printing circuit.

The mechanism controlled by the printing magnet 11 is shown in Fig. 2. Type bars 20 are carried by crosshead 21 which is slideable, vertically, on rods 22. The spring-pressed arms 23 pivoted to the crosshead have their free ends abutting the lower extremity of the type bars, so that as the crosshead moves upwardly, the type bars are urged in the same direction. The reciprocating movement of the crosshead is controlled from either the listing shaft 24 or the total taking shaft 25. The former carries a cam 26 and the latter a cam 27; which cams are adapted to rock shaft 28, through follower mechanism designated 29. Shaft 28 carries arms 30, which are connected by links 31 to the crosshead.

As the type bars move upwardly, the type elements 32 will successively pass printing position opposite platen 33 and ratchet teeth 34 will successively pass the nose of the stop pawl 35. Energization of magnet 11 will trip latch 36 permitting stop pawl 35 to engage one of the ratchet teeth 34, thus positioning the corresponding type element opposite the platen.

For the purpose of the present invention, an auxiliary crosshead 37 is provided which is slideable upon rods 38. The cross head 37 is link connected with a lever 39, pivoted at 40 and having its shorter arm connected by a link 41 to an arm 42, secured upon shaft 28. With this arrangement, the crosshead 37 moves upwardly in unison with the crosshead 21. Carried by crosshead 37 are adjustable camming elements 43, one for each type bar. Each element is adapted to cooperate with an interposer 44, pivoted to and depending from arm 23. The operation of the mechanism is such that as the crossheads move upwardly, the parts maintain the same relative positions they occupy in Fig. 2. Upon the energization of magnet 11, however, and the consequent interruption of further upward movement of type bar 20, the lower extremity of the bar will become a fulcrum for the free end of arm 23. The pivot point of arm 23 will, of course, continue its upward movement with the crosshead 21 so that the interposer 44 will now move upwardly at a greatly reduced rate.

The camming element 43, moving upwardly with crosshead 37 will force the free end of interposer 44 toward the left momentarily, as the camming portion of element 43 passes the camming surface of the interposer.

In alignment with interposer 44 is a link 45, carried by a pair of bell cranks 46 and 47, which are connected for parallel movement by a link 48. Movement of interposer 44 toward the left will cause a corresponding movement of associated links 45 and the extending nose 49 thereof will cause closure of a pair of contacts 50. For convenience in construction, alternate links 45 have

the extensions 49 at opposite extremities in engagement with associated contacts 50, and the related contacts 50 are similarly staggered as shown in Fig. 4.

Briefly then, the energization of the printing magnet will interrupt the type bar 20 with a printing element in position. Immediately following the interruption of the type bar movement the resultant relative movement between interposer 44 and camming element 43 will cause momentary closure of the associated pair of contacts 50.

It is these contacts that control the operation of the accumulator mechanism in the manner to be described presently.

Referring now to Fig. 1, the contacts 50 have their one blade connected to a pair of plug sockets 51 and the other blade to a pair of plug sockets 52. In positions in which it is desired to have adding accompany printing, a plug connection 55 is made between sockets 13 and 52 and a further connection 53 is made between socket 51 and one of a pair of sockets 54, which are wired to adding magnets 10. With this arrangement, the circuit from the lower brushes which extends through the plug connection 12 as traced above, will branch at plug socket 13 through connection 55, contacts 50, connection 53, adding magnet 10, to line 19. It will be noted, however, that the completion of this circuit which parallels the printing magnet circuit, traced above is effected slightly after the completion of the printing magnet circuit and is dependent upon the time of closure of contacts 50. Since the adding circuit also passes through the card perforation, it is apparent that the action of the mechanism which results in closing contacts 50 must be very rapid. In commercial machines it is desirable to have greater operating tolerances and in such case the accumulators which receive entries through contacts 50 are timed later; that is, their time of clutch disengagement is delayed; than the accumulators that receive entries directly from the analyzing brushes.

When the accumulator is thus timed, the plug connection 55 is not made, but instead a substitute connection is made from socket 52 to one of the sockets 81 so that upon closure of contacts 50 a circuit is completed from line 14, wire 87, contacts L31 (timed as in Fig. 5 in synchronism with the retarded accumulator), wire 88, socket 81, connection to socket 52, contacts 50, socket 51, connection 53, socket 54, adding magnet 10 to line 19. Thus according to Fig. 5 the adding circuit is completed about a point and a half after the printing circuit.

The mechanism controlled by adding magnet 10 is shown in Fig. 3. This adding mechanism is of the well-known Hollerith type, and is described in detail in the application above referred to. Its operation briefly is as follows:

A shaft 51 is driven in the usual manner in synchronism with the card feeding mechanism so as to make one revolution for each card passing through the machine. Attached to shaft 51 and rotating herewith, are clutch elements 58 which are shiftable along the shaft to engage the other faces 59 of the clutches. These latter elements are integral with gears 60 which mesh with gears 61 associated with the usual numeral or index wheels 62, freely carried on shaft 63. Each clutch element 58 is normally urged toward its related element 59 by a pivoted lever 64, which is urged in a counterclockwise direction by a leaf spring 65. Movement in this direction is normally prevented by means of an ar- 75

ture latch 66 which engages a block 67 to hold the arm 64 in the position shown in Fig. 3. When magnet 10 is energized, the latch 66 is released and the driving element 58 engages 59 to cause 5 rotation of the index wheel 62.

At the end of each revolution of shaft 57, the clutch 58 is mechanically disengaged in the usual manner so that the amount of rotation imparted to the index wheel 62 is dependent upon the time 10 in the cycle in which magnet 10 is energized. Thus, if magnet 10 is energized at the "5" time, wheel 62 will be advanced five steps.

Associated with each adding wheel is a total read-out device, which consists of a commutator 15 68, provided with segments 69 corresponding in number and position to the several digit indicating positions of the index wheel. A brush structure 70 is carried by and insulated from a gear 71, meshing with gear 60, so that the brush structure 20 70 is angularly displaced an amount corresponding to the reading on the numeral wheel. The structure carries two brushes, one of which engages the segments 69, and the other engages a common segmental conductor 72, whose contacting surface is concentric with the supporting 25 shaft of gear 71. The segments 69 and conductors 72 are diagrammatically represented in developed form in the circuit diagram, Fig. 1.

Each group of segments 69 corresponding to the 30 same digit is connected to a common conducting wire 73, whereby all the "9" segments are in multiple, all the "8" segments are in multiple, and so on. An emitter 14, shown diagrammatically in Fig. 1, is driven in synchronism with the 35 movement of the printing crossheads, during total taking operations. This emitter consists of a double brush structure 75 which may be mounted on the total taking shaft 25 of Fig. 2. One of the brushes 75 is adapted to successively contact with the segments 76 as the correspondingly numbered 40 type elements pass through printing position during total taking operations.

Each segment 76 is connected to the correspondingly numbered wire 73 through a cable 77. Hence, it will be understood that each of the 45 commutator segments 69 receives a timed impulse from the emitter at the time when the type corresponding to the wheel setting is passing the printing line.

During total taking operations, a relay magnet 50 18 is energized to connect the common conducting strips 72 to the corresponding printing magnets 11, by causing closure of contacts 18b. A representative circuit will be traced to illustrate the manner in which the printing mechanism may be actuated from the total taking devices. Assuming the digit 5 to be set on one of the commutators 69, 72; during the total taking cycle, as the brushes 75 of emitter 74 rotate in synchronism with the operation of the printing mechanism, a circuit will be completed from right side of line 14, contacts 78, common segment 79, brushes 75, "5" segment 76, cable 77, "5" wire 73, "5" segments 69, brush 70 (dotted in the units order position of Fig. 1), common conductor 72, contacts 18b, printing magnet 11, to left side of line 18. In this manner, the value standing on the read-out device of the accumulator will be printed and, as during listing operations, the contacts 50 will be closed when the upward movement of the type bar is interrupted. However, since the accumulating mechanism is inoperative during total taking operations, this closure of contacts 50 will have no effect.

75 The closure of contacts 50 is utilized, however,

for checking purposes which will be more fully described presently. Where checking of the printing in several positions of the record is desired as on a gas or electric bill where printing of data is duplicated in several sections of 5 the bill, a comparison is made of the setting of the type bars that control the printing in the selected columns. It will be appreciated that if a type bar in any section is retarded due to stickiness, an erroneous figure will be printed and the 10 data will not be in proper duplicate. For this purpose, the contacts 50 are utilized and where a plurality of type bars are to print the same information, corresponding contacts 50 will close at the same time, if all the bars are interrupted 15 in the same printing position.

If the contacts 50 are connected in series, a circuit will be completed at the time corresponding to the selected figure. However, should one of the type bars not be interrupted at the same 20 time as the others or if it had been interrupted earlier, this series circuit would then not be completed and its failure would cause stopping of the machine and operation of a single device to inform the operator of the non-correspondence 25 between the printed items.

The checking arrangement operates with equal 30 facility during listing and total taking operations, so that either listed items may be compared with one another, or totals may be so compared. 30 The manner of operation of the checking circuit may best be explained by way of example with special reference to the circuit diagram of Fig. 1.

Let us assume that comparison is to take place 35 between the items printed in the positions corresponding to the 2, 7, and 8 orders of the accumulator, although it will be understood that the comparison is not restricted to positions within in a single accumulator, but may occur between different orders in different accumulators. 40

A plug connection 80 is inserted between one of a number of sockets 81 and the socket 52 of the contacts 50 associated with one of the positions to be checked. Series plug connections 82 are then made as indicated to connect the several orders to be checked, in series. The socket 51 of the last pair of contacts is then connected by a plug connection 83 to a socket 84 of a double wound relay magnet 85.

Where more than one denominational order is 50 to be checked, similar connections are made between the contacts of that order, and another of the magnets 85 so that if two place figures are to be checked, two magnets 85 are utilized, and if four places are to be checked, the four magnets will be separately connected as explained for the one order. 55

Where a lesser number than all of the magnets 85 are required, a plug connection 86 is made between the socket 84 of each unused position, 60 and one of the sockets 81.

During item printing operations, cam contacts L31 send a series of impulses to the plug sockets 81, timed as indicated on the time chart Fig. 5. Assuming that the three type bars associated with 65 the three contacts 50 connected as shown, are all interrupted at the same printing positions, the closure of contacts L31 at such time will complete a circuit from line 14, wire 87, contacts L31, wire 88, socket 81, plug connection 80, thence serially 70 through the three contacts 50, which are all momentarily in closed position, connection 83, to left-hand winding of magnet 85, to line 19. Energization of the left-hand winding of magnet 85 will cause closure of contacts 85a and 85b, the 75

former providing a holding circuit from line 14, wire 87, contacts P12, L32, contacts 85a, right-hand winding of magnet 85, to line 19. This circuit is maintained until contacts L32 open at the 5 end of the listing. During total taking operations, contacts P12 open at a corresponding time. After the type bars have completed their upward movement, all the contacts 85b will be in closed position, if there is agreement between 10 the positions selected for checking.

If there is any disagreement, one or more of the contacts 85b will be in open position. The series circuit through the contacts 85b is used to cause stopping of the machine and the illumination of a suitable signal lamp. This is brought about in the following manner. Inserted in the card feed clutch circuit are a pair of relay contacts 103b controlled by a relay magnet 103. These contacts are in series with the usual stop 15 key contacts SP, and their opening has the same effect as the operation of the stop key; that is, they interrupt the further operation of the machine. Magnet 103 is normally deenergized to enable contacts 103b to permit closure of the 20 start circuit. The circuit for magnet 103 follows, when completed by closure of contacts 100a, from left side of line 19, through wire 101, normally closed contacts 104, relay magnet 103, contacts 100a, to line 14. Contacts 100a are controlled by 25 a relay magnet 100 which is energized when there is a disagreement. It is normally maintained energized by a circuit from line 19, wire 101, contacts L33, P13, wire 102, magnet 100, to line 14. Thus magnet 103 is normally deenergized and its 30 contacts 103b normally closed. The contacts L33 open momentarily once during each adding cycle of the machine and contacts P13 open during each total taking cycle. The series circuit through contacts 85b provides a shunt around the contacts L33 and P13 so that the circuit of 35 magnet 100 will be maintained during the period that the cam contacts P13 or L33 are open. However, this shunt circuit is effective only if the compared positions are in agreement.

If a disagreement occurs, the shunt circuit will 40 be open at the time when either contacts L13 or P13 open. Magnet 100 will thereby be deenergized, opening its relay contacts 100a, completing the circuit of magnet 103 and causing stopping of the machine due to the opening of contacts 103b. At the time of energization of magnet 103, a second pair of contacts 103a will close 45 to set up a circuit from line 14, signal lamp 105, contacts 103a, magnet 103, contacts 104, wire 101, to line 19. This circuit is maintained until 50 contacts 104 are opened by manual operation.

As explained in the above mentioned application, the machine automatically resumes card feeding operations following each total taking 55 operation. This is effected by completion of a so-called automatic start circuit effective upon closure of contacts P2 near the end of the total taking cycle. In the present machine, this circuit includes contacts 103b, which as seen above, are opened and held open as the result of a disagreement in the several items or several totals 60 printed.

During total taking operations an emitter 106 functions to send a series of timed impulses to sockets 81 in the same manner as cam contacts 70 L31 do during listing operations.

While there has been shown and described and pointed out the fundamental novel features of the invention as applied to a single modification, it will be understood that various omis-

sions and substitutions and changes in the form and details of the device illustrated and in its operation may be made by those skilled in the art without departing from the spirit of the invention. It is the intention therefore to be limited only as indicated by the scope of the following claims. 5

What is claimed is as follows:

1. In a tabulating machine having printing mechanism including a type bar provided with 10 type elements movable to and through a printing position, an entry controlling means comprising a pair of contacts in sequence in an entry controlling circuit, a crosshead for carrying and moving said bar, means for interrupting further 15 movement of said bar with said cross-head at differential times to select the type elements for printing and means operative upon interruption of the movement of the bar for causing the operation of said pair of contacts whereby said circuit will be closed at a differential time in accordance with the value of the character selected for printing.

2. In an accounting machine, a differentially positionable printing type bar, control means for 25 controlling the positioning of the same, and electrically operated control means for controlling operation of an accumulator, and means whereby said type bar effects the operation of said accumulator control means to cause the latter 30 to effect an operation of said accumulator only on the positioning of the type bar to select a character for printing.

3. In a tabulating machine, a printing cross-head, means for causing an invariable excursion 35 of said crosshead, a type bar resiliently carried thereby, means for interrupting the movement of said bar with said crosshead, an accumulator control means and means operative immediately upon the interruption of movement of said bar 40 for causing an operation of said accumulator control means dependent upon the stopping position of the bar.

4. A tabulating machine having record analyzing means, printing mechanism comprising 45 a reciprocable type carrier having character representing type thereon, reciprocating means therefor, means controlled by the analyzing means to control the positioning of said character representing type for printing in accordance with record analysis, accumulator controlling contacts operated by said type carrier at differential times upon positioning of the same to select a character representing type for printing, and means controlled by said type carrier for 50 causing the operation of said contacts at differential times upon the positioning of said type carrier for selection of said character representing type.

5. A tabulating machine having record analyzing means, printing mechanism comprising a differentially positionable type carrier, having character representing type thereon, moving means therefor, means controlled by the analyzing means to control the positioning of said character representing type for printing in accordance with record analysis, an accumulator entry control means operated by said type carrier upon positioning of the same to select a character representing type for printing and means 70 controlled by said type carrier for causing the operation of said entry control means upon positioning of the type carrier for selecting said character representing type.

6. In combination, a type bar arranged to take 75

different character representing positions, means for differentially positioning the same under control of differentially timed electrical impulses, means for moving said bar to position the latter, 5 impulse transmitting means for a circuit for a controlling device operable in response to differentially timed electrical impulses, and means

controlled by said type bar upon the positioning of said bar for operating said impulse transmitting means for sending an electrical impulse to said circuit at a differential time in accordance with the value of the character represented by 5 the position of the type bar.

CLAIR D. LAKE.
